(57) **CLAIM**

The ornamental design for key blade blank, as shown and described.

DESCRIPTION

FIG. 1 is a front elevational view of a key blade blank showing my new design;

FIG. 2 is a bottom plan view thereof;

FIG. 3 is a left side elevational view thereof;

FIG. 4 is a right side elevational view thereof;

FIG. 5 is a rear elevational view thereof;

FIG. 6 is an enlarged scale fragmentary front and bottom perspective view thereof; and,

FIG. 7 is an enlarged scale sectional view taken along line 7—7 of FIG. 1.

The portions in broken lines are for illustrative purpose only and from no part of the claimed design.
